UNITED STATES PATENT OFFICE

JACOB I. RUSSAKOV, OF CHICAGO, ILLINOIS

DESIGN FOR A WASHING MACHINE

Application filed November 15, 1930. Serial No. 37,676. Term of patent 14 years.

To all whom it may concern:

Be it known that I, JACOB I. RUSSAKOV, a citizen of the United States, residing in Chicago, Cook County, Ill., have invented a new, original, and ornamental Design for Washing Machines, of which the following is a specification, reference being had to the accompanying drawings forming a part hereof.

The single figure of the drawings is a perspective of a washing machine in accordance with this design.

I claim:

The ornamental design for a washing machine substantially as shown.

JACOB I. RUSSAKOV.
